UNITED STATES PATENT OFFICE.

THOMAS HOGAN, OF TORONTO, CANADA, ASSIGNOR OF ONE-HALF TO
JAMES WILSON, OF OTTAWA, CANADA.

NON-REFILLABLE BOTTLE.

SPECIFICATION forming part of Letters Patent No. 638,636, dated December 5, 1899.

Application filed November 5, 1897. Serial No. 657,584. (No model.)

To all whom it may concern:

Be it known that I, THOMAS HOGAN, of Toronto, in the Province of Ontario and Dominion of Canada, have invented certain new and useful Improvements in Non-Refillable Bottles; and I do hereby declare that the following is a full, clear, and exact description of the same, reference being had to the accompanying drawings, forming a part hereof.

10 My invention, which will be hereinafter fully set forth and claimed, relates to devices for preventing bottles from being refilled.

The object of my invention is a bottle that cannot be refilled.

15 Figure 1 is a vertical section through the center of my improved bottle, showing the same as filled and stoppered. Fig. 2 is a partial vertical section of the neck and stopper, taken at a right angle to Fig. 1 and showing 20 the stopper-locking device. Fig. 3 is a top view of the stoppered mouth of the same. Fig. 4 is a horizontal section of the same on line 4 4, Fig. 1. Figs. 5, 6, 7, and 8 are horizontal sections of the same on lines 5, 6, 7, 25 and 8, respectively, of Fig. 1.

My improved non-refillable bottle consists of two main parts, the bottle proper, A, and the stopper B, and the latter again is composed of several separate parts.

30 The bottle A has in the interior of its neck, some distance from the mouth, a downwardly-facing annular shoulder a, Figs. 1 and 2, serving as an abutment for projecting stops in the stopper. A vent is provided in the bottom a'. This consists of a passage 2 angular in direction, (and which may be double, as shown in Fig. 1,) having its outer orifice or orifices out of the center and diverging to a small central passage 3, opening into a co-35 noidal chamber 4 and ending in a central tubular passage 4'. The chamber 4 is a valve-chamber with a true bottom a'' and true top a''', as valve-seats, in a raised part A' and containing a valve C. From the upper conical valve-seat a'' passages 5 diverge downwardly and outwardly through the raised portion A', Figs. 1 and 8, communicating with the interior of the bottle. The bottom of the valve C is the valve-face adapted to making 45 a tight joint with the bottom of the chamber or valve-seat a'' and closing the passage 3 when down, and the top, being conical, is the

valve-face for the conical seat a''', adapted to close the passages 5 when raised. The valve C conforms in shape to the upper portion a''' 55 of the chamber 4, but has at the top a recess or indentation c, adapted to receive the end of a wire to limit its traverse.

The stopper consists of a plug D, of hard or non-elastic material, either cylindrical or conical, filling the neck of the bottle with an easy fit and reaching below the shoulder a. Its upper end projects outwardly and downwardly, forming an overhanging lip d and an annular groove 6, the bottom or lower edge 60 of which lip is approximately level with the top of the bottle, (presuming the latter to be flat,) as shown. A groove 7 is preferably formed in the outer edge of the mouth of the bottle, adapted to receive the lower edge of 70 the lip d of the stopper. In the groove 6 is placed an elastic packing-ring D', adapted to make a tight joint between the bottle-mouth and the stopper, the latter being not necessarily tight in the neck of the bottle. 75

In the upper end of the plug D is a central passage 8, Figs. 1 and 3, extending some distance down and terminating in a wide but shallow chamber 9. Around the outer margin of the bottom of said chamber are formed 80 a series of small passages 10, Figs. 1, 4, and 5, extending downward and terminating in the sides of a valve-chamber 11, Fig. 1, having the form of a truncated conoid. This chamber has a recess or cavity 12, Figs. 1 and 85 5, of about the same diameter as the passage 8, extending upward a short distance, but not into the chamber 9. The bottom of said chamber forms a valve-seat d⁰³ and has a downward central passage 13, terminating a 90 little lower down in another laterally-extended shallow valve-chamber 14, in which the top forms a valve-seat d⁰⁴. The bottom of this chamber 14 has a wide-mouthed conical recess 15, Figs. 1 and 6, terminating in a 95 downward passage 16 coextensive with the plug D. At the outer margin of the bottom of the chamber 14 are a series of passages 17, extending downward coextensive with the plug. The entire margin of the chamber 14 is, however, not perforated by passages 17; but two opposite spaces, one on each side, are spared out to afford room on each side for a recess 18, Figs. 2 and 7, just below the shoul-

der a , having its bottom sloping slightly inward and downward. Each recess is adapted to contain, loosely and flush with the outer surface, a small block D'' , which has its bottom d'' beveled downward and inward, the bevel being more acute than that of the bottom of the recess. Thus when said block stands free in its recess it is bound to incline outwardly and project its upper end out of the recess, as shown in Fig. 2, the upper end just passing under the shoulder a , and thus forming an interlocking stop against said shoulder and preventing the withdrawal of the stopper from the neck of the bottle.

15 The valve-chamber 11 contains a valve D^3 , its face d''' downward, normally resting on the bottom or valve-seat d^3 and its upper part or stem projecting into the recess 12 and being allowed a suitable rise therein if the bottle is inverted, so as to allow the valve to leave its seat.

15 The valve-chamber 14 15 contains a valve D^4 , which normally rests in the recess 15 with its face d^4 upward, separated from the top of the chamber or valve-seat d^4 , and its stem extending into the passage 16. Said stem is provided with a non-corrosive wire d^5 , extending down through the passage 4' into the chamber 4 and in the recess c of the valve C, 25 not reaching, however, to the bottom of said recess, but leaving a space between the end of the wire and said bottom, so as to allow the valve C to rise from the lower seat without necessarily seating in the upper seat. On 30 said wire d^5 is secured a float d^6 , placed a little distance below the lower end of the plug D. The wire d^5 is preferably made in two lengths for convenience in manufacture and for adjustment, the joint being within the 35 float d^6 .

40 The operation of the device is as follows: The bottle is filled and the stopper is inserted with the wire d^5 and float d^6 , the wire being passed into the passage 4' and recess c . 45 During the insertion of the stopper the stops D'' are held in place by the inner face of the neck of the bottle. When the stopper is pushed down far enough to compress the elastic ring D' rather more than is desired for a 50 final compression, the upper end of the stops D'' pass the shoulder a , and their outward support being thus removed they fall outward under said shoulder and form an abutment between the bottle-neck and stopper and the 55 latter cannot be withdrawn.

55 In emptying the bottle the latter is reversed and the float d^6 rises in the liquid with which the bottle is filled and lifts or keeps the valve D^4 from its seat d^4 in the chamber 14, thus allowing the liquid to pass through the passage 17 into the valve-chamber 14 and thence into the passage 13. As the bottle is reversed the valve D^3 drops by its own weight from its seat and allows the liquid to pass into the 60 chamber 11 and thence by the passage 10 into the chamber 9 and issue from the passage 8, which forms the mouth of the stopper. While

the bottle is emptying, held reversed, the valve C in the vent drops from its seat a'' and is held up by the wire d^5 , which latter prevents it from dropping on its conical seat a''' . The passages 2, 3, 4, and 5 are thus open and free for communication with the interior of the bottle, and air passes through the same to fill the void of the liquid escaping by the 75 mouth of the bottle. When all the liquid has escaped and the bottle is empty, the float d^6 is no longer being supported and therefore drops, and with it the wire d^5 and valve D^4 , the latter closing the passage 13 and the end of the 80 wire d^5 allowing the valve C to drop into its upper (lower when bottle is reversed) seat a''' and close up the passage 5. The vent is thus closed also and becomes useless as a means for refilling. A cork may be inserted in the 85 mouth of the passage 8 for convenience in carrying the bottle upside down when filled. When the bottle is empty and held upright, the valve D^4 is open, but the valve D^3 is closed, and any liquid poured in from the top 90 through the passages 8, 9, and 10 could not pass farther than the chamber 11 and could not enter the passage 13.

I claim as my invention—

1. In a non-refillable bottle, the combination 95 with the bottom of an internal raised portion, a valve-chamber in said raised part having its bottom and top formed into valve-seats, an outward central passage from the bottom of said chamber and laterally-deviating continuations of said passage having one or more external orifices out of a straight line from said central passage, radiating passages from the upper valve-seat communicating with the interior of the bottle and a valve in said chamber 100 having its lower and upper surfaces formed into valve-faces adapted to fit the valve-seats in said chamber and close the passages therefrom to the exterior and interior, substantially as set forth.

110 2. In a non-refillable bottle, the combination with the bottom of the bottle of a raised portion, a conoidal chamber in the said raised portion having its base and conical truncated top formed into valve-seats, a central downward passage from the bottom of said chamber, a laterally-deviating continuation of the said passage with one or more external orifices, passages from the conical valve-seat to the interior of the bottle, a truncated conoidal 115 valve within said chamber having its base and conical top formed into valve-faces, a recess or indentation in the top of said valve, a tubular upward continuation of the valve-chamber and a movable pin passing through 120 said tubular upper passage into the recess of the valve and limiting its rise, substantially as set forth.

125 3. In a non-refillable bottle, the combination 130 with the bottom of the bottle of a central raised portion, a valve-chamber within said raised portion, having a lower and upper valve-seat, a tubular passage from the top of said valve-chamber, a passage from the lower

- valve-seat to the exterior having several changes of direction, passages from the upper valve-seat to the interior of the bottle, a valve in said chamber having a lower face and an upper valve-face adapted to close the passage to the exterior and interior respectively, a recess in the top of said valve, a pin or wire passing into said recess through the upper tubular passage in the raised portion, 5 and a stopper in the neck of the bottle, a valve-chamber in said stopper, a valve in said chamber to which said wire is attached and a float a little distance below said stopper, substantially as set forth.
- 10 4. In a non-refillable bottle, the combination with the neck of a non-elastic plug adapted to make a tight joint at the mouth of the bottle, a central passage in the upper end of said plug, an extended shallow chamber at the lower end of said passage, a series of small downward passages at the outer margin of said chamber, a conoidal chamber at the lower end of said marginal passages, a central downward passage from the bottom of said chamber, a valve having the bottom of said chamber for a valve-seat and adapted to close the orifice of said last-named passage, a laterally-extended shallow chamber at the lower end of said passage having its top formed into a 15 valve-seat, a valve in said chamber adapted to close the lower orifice of said passage in the top of said chamber and a series of passages from the margin of said chamber downward, substantially as set forth.
- 20 5. In a non-refillable bottle, the combination with the neck of a downwardly-facing annular shoulder, a non-elastic plug in said neck, stops in said plug adapted to interlock with said shoulder, two chambers in said plug one 25 above the other, a central passage connecting said valve-chambers the faces of the chambers at the ends of the passage formed into valve-seats, passages at the margin of the
- lower chamber to the lower end of the plug, 30 passages at the margin of the upper chamber to another higher chamber, a central passage from said last-named upper chamber to the upper end of the plug and valves in said two lower chambers adapted to close the orifice of the connecting-passage at one end or the other, 35 substantially as set forth.
6. In a non-refillable bottle, the combination with the neck of a downwardly-facing shoulder, a non-elastic plug in said neck adapted to interlock with said shoulder non-withdrawably, a chamber in said plug having its top formed into a valve-seat, a conical recess in the bottom of said chamber, a terminal passage at the bottom of the recess to the lower end of the plug, passages from the outer margin of said chamber to the lower end of said plug, an upward central passage from said chamber, a valve in said chamber having its top formed into a valve-seat adapted to close the orifice of said upward passage, a wire secured to the stem of said valve passing through the lower terminal passage, a float on said wire a little distance below the lower end of said plug, a raised portion on the bottom of said bottle having an upper central passage 40 through which said wire passes, a valve-chamber in said raised portion having upper and lower valve-seats, vent-passages in the upper and lower part of said chamber, a valve in said chamber adapted to close said vents, 45 a recess in the top of said valve adapted to be engaged by said wire and controlled thereby, substantially as set forth.
- 50 7. In testimony whereof I have signed my name in the presence of the undersigned witnesses.
